DRAPEY PLEATER CLIP

Ralph Romano, Levittown, Pa., assignor of ten percent to
Harold B. Lipsius, five percent to Samuel Saewitz, and
ten percent to Arthur H. Seidel

Filed Apr. 18, 1966, Ser. No. 1,958

Term of patent 14 years

(Cl. D21—1)

FIGURE 1 is a perspective view of a drapery pleater clip, showing my new design;

FIGURE 2 is a side view thereof;

FIGURE 3 is a front view thereof;

FIGURE 4 is a rear view thereof;

FIGURE 5 is a top plan view thereof;

FIGURE 6 is a bottom plan view thereof.

The side opposite the side shown in FIGURE 2 is a mirror image thereof.

I claim:

The ornamental design for a drapery pleater clip, substantially as shown and described.
